United States Patent

Des. 239,902
Patented May 18, 1976

239,902

CORNER SHELF UNIT

George V. Goulder, 2701 Eaton Road,
Shaker Heights, Ohio 44118

Filed Jan. 2, 1975, Ser. No. 538,110

Term of patent 14 years

Int. Cl. D6—04

U.S. Cl. D6—186

FIG. 1 is a perspective view of a corner shelf unit showing my new design;

FIG. 2 is a top plan view;

FIG. 3 is a front elevational view;

FIG. 4 is a left side elevational view taken along line 4—4 of FIG. 2;

FIG. 5 is a back elevational view taken along line 5—5 of FIG. 2; and

FIG. 6 is a bottom plan view.

I claim:

The ornamental design for a corner shelf unit, as shown.
